D. L. HALL

DENTAL FILM HOLDER

Filed Sept. 12, 1921

A. D. Wright. Attorney

UNITED STATES PATENT OFFICE.

DANIEL L. HALL, OF COLUMBIA, SOUTH CAROLINA.

DENTAL FILM HOLDER.

Application filed September 12, 1921. Serial No. 499,934.

To all whom it may concern:

Be it known that I, DANIEL L. HALL, a citizen of the United States, residing at Columbia, in the county of Richland and State of South Carolina, have invented certain new and useful Improvements in Dental Film Holders, of which the following is a specification, reference being had therein to the accompanying drawing.

10 This invention relates to certain new and useful improvements in dental film holders for making radiographs of the teeth, the object being to provide a holder which will hold the film pack within the mouth of the patient at approximately right angles to the rays so as to prevent the images on the negatives from being distorted.

15 A further object of the invention is to provide a holder which is so constructed that it can be adjusted for taking radiographs of the uppers and lowers, the position of the film pack in the mouth being determined by the position of the handle so that the patient as well as the photographer 20 can readily adjust the film pack within the mouth in order to enable the rays to strike the film at approximately right angles under all conditions.

25 A still further object of the invention is to provide a film holder which is exceedingly simple and cheap in construction and one which is capable of being adjusted into a number of positions so that the film can be held at the proper angle for taking uppers and lowers on either side.

30 Other and further objects and advantages of the invention will be hereinafter set forth and the novel features thereof defined by the appended claims.

35 In the drawings,

Figure 1 is a perspective view of a dental film holder constructed in accordance with my invention showing a film pack in position in dotted lines;

40 Figure 2 is a longitudinal section partly broken away;

Figure 3 is a section taken on line 3—3 of Figure 2; and

45 Figure 4 is an elevation partly broken away showing the holder adjusted in various positions in dotted lines.

In the drawing 1 indicates a handle herein shown formed of a loop of metal having its end portions 2 bent back over a filler 3

and secured by a rivet 4. The filler 3 terminates short of the end portions 2 and has its ends cut off to form oblique shoulders 5 and 6 as clearly shown in Figure 3.

While I have shown a handle constructed in this particular manner I am aware that the same can be constructed in various other ways, as for instance, a handle could be formed solid with a bifurcated end and I do not wish to limit myself to the details of construction herein shown.

60 Pivotedly mounted between the end portions 2 of the handle on a rivet 7 is an arm 8 having lateral projections 9 and 10 provided with oblique faces adapted to cooperate with the oblique shoulders 5 and 6 for supporting the arm at right angles to the handle as clearly shown.

65 Slidably mounted on the end portions 2 of the handle is a locking collar 11 which is adapted to embrace the projections 9 and 10 and hold the oblique faces in contact with the oblique shoulders as clearly shown in Figure 3 for rigidly locking the arm at right angles to the handle upon either side as shown in Figure 4. The movement of the locking collar is limited by a stop pin 12 extending transversely through the end portions 2 in filler 3.

70 Pivotedly mounted on the extreme end of the arm 8 is a film pack holder 13 composed of a vertical member 14 against which the film pack is adapted to be placed, said member having a lateral projecting portion 15 forming a support for the lower edge of the film pack, said lateral projecting portion 80 being provided with a flange 16 for holding the film pack against the member 14.

75 Extending laterally from the flange 16 is a projection 17 which is adapted to engage the teeth so as to position the film pack within the mouth of the patient while making the radiographs.

80 The holder is preferably formed of aluminum which is easily penetrated by the rays so as to prevent shadows from being formed 90 on the negative when a radiograph is being made.

85 I have found from practical experience that it is very difficult to hold a film pack in position within the mouth at the proper angle so as to make a negative of the teeth which will show the apex of the teeth properly as there is nothing to actually determine 100 105

- the position of the film pack within the mouth of the patient, while with my device I provide means for holding the film pack in such a manner that the patient grips the holder so that the film pack will be held in the mouth to enable the entire tooth to be taken and by having the arm arranged at right angles to the handle, the angle of the film pack within the mouth can be adjusted 5 and held by the patient so as to prevent the images on the negatives from being distorted as if the film pack is not held at approximately right angles to the X-ray tube the image will either be shortened or lengthened. 10 15 From the foregoing description it will be seen that I have provided a dental film holder composed of a handle having an arm pivotally mounted thereon capable of being adjusted and locked at right angles to the handle on either side, said arm carrying a pivoted holder which can be inverted so as to hold a pack for taking uppers and lowers. 20 25 By forming the holder in the particular manner shown the film pack can be placed in position upon the support and bent so as to conform to the curvature of the teeth. While I have shown certain details of construction I do not wish to limit myself to any particular manner of constructing the various parts as 30 35 I am aware that various changes can be made without departing from the spirit of my invention.

What I claim is:—

1. A film holder comprising an arm adjustably mounted on said handle and mounted to swing in the same plane of the handle and a film holder carried by the end of the arm and mounted to swing in the same plane as the arm. 40
2. A film holder comprising a handle having an adjustable arm and mounted to swing in the same plane as the handle and a film pack supporting member having a lateral projection for engaging the teeth adjustably

mounted on said arm and mounted to swing 45 in the same plane as the arm.

3. A film holder comprising a handle having an arm pivotally mounted thereon, means for locking said arm at right angles to said handle and a film pack holder pivotally mounted on the end of said arm and mounted to swing in the same plane as the arm. 50

4. A dental film holder comprising a handle having a bifurcated end, an arm pivotally mounted in said bifurcated end having projections provided with oblique faces, said handle having oblique shoulders adapted to be engaged by said oblique faces, a locking sleeve slidably mounted upon said handle for locking said arm at right angles to said handle and a film pack holder carried by the free end of said arm. 55 60

5. A film holder comprising a handle, an arm movably carried by the handle and a film pack support movably carried by the free end of said arm, said arm and pack support being mounted to move in the same plane. 65

6. A film holder comprising a bifurcated handle having an arm pivotally mounted therein, said arm being capable of swinging to either side of the handle, means for limiting the swinging movement of said arm for holding said arm at right angles to said handle, means for locking said arm in adjusted position and a film holder pivotally mounted on the free end of said arm. 70 75

7. A dental film holder comprising a pivoted arm having a pivoted film holder mounted on the free end thereof, said pivotal film holder being capable of being swung to either side of said arm, said arm and holder being mounted to swing in the same plane. 80 85

In testimony whereof I hereunto affix my signature.

DANIEL L. HALL.
